LIMIT CONTROL

Filed Sept. 5, 1947

UNITED STATES PATENT OFFICE

2,561,054

LIMIT CONTROL

Howard E. Hodgson, Wauwatosa, and Richard R. Ranson, Whitefish Bay, Wis., assignors to Cutler-Hammer, Inc., Milwaukee, Wis., a corporation of Delaware

Application September 5, 1947, Serial No. 772,444

10 Claims. (Cl. 318—468)

1

This invention relates to limit controls and is particularly applicable for limit switch drives for use in connection with apparatus such as motor driven sluice-gates having an exceedingly long range of travel.

The invention has among its objects to provide a limit switch driving mechanism which enables limit switches of various types having a relatively short operating range to be used in the control of apparatus such as motor driven sluice gates which require an exceedingly long range of travel and exceedingly accurate control within short zones at opposite ends of such range.

Another object is to provide a limit switch driving mechanism for the aforesaid purpose which operates to drive an associated limit switch during travel of the gate through predetermined parts of its range and to positively lock the same against operation during travel of the gate through the remainder of its range.

Another object is to provide a limit switch operating mechanism of the aforesaid type which is simple and rugged in construction, positive and reliable in operation and which operates to insure exact registry of the limit switch with respect to the gate operating mechanism at all times.

Various other objects and advantages of the invention will hereinafter appear.

The accompanying drawing illustrates an embodiment of the invention which will now be described; it being understood that the embodiment illustrated is susceptible of modification without departing from the spirit and scope of the appended claims.

In the drawing,

Figure 1 diagrammatically illustrates a motor operated sluice gate having a limit switch driving mechanism embodying the invention associated therewith;

Fig. 2 is a schematic view of the limit switch driving mechanism illustrated generally in Fig. 1, and

Fig. 3 is a sectional view on line 3—3 of Fig. 2.

Referring to Fig. 1, the same illustrates a sluice gate 1 and a driving motor 2 therefor, which is shown as being operatively connected to said gate through the medium of a conventional gear drive comprising a driving pinion 3 and associated rack 4 which is fixed to said gate. It is assumed that the gate has a long range of travel, as for example 125 ft., between closed and raised limits marked CL and RL and that the same must be accurately controlled within a zone Z¹ at the lower end of said range which may ex-

tend for a distance of 20 ft. and within a zone Z² at the upper end of said range which may extend for a distance of 5 ft. The control means for motor 2 includes a limit switch LS which may be of the traveling nut type and may be provided with various control contacts for effecting slowdown and stopping of the motor during movement of gate 1 into its raised and closed limits. In accordance with the present invention the operating screw 5 of limit switch LS is operatively connected to gate 1 through the medium of a driving mechanism 6 which operates as herein-after set forth to drive said screw during movement of the gate in zones Z¹ and Z² and to lock said screw against operation during movement of the gate through the remainder of its range.

As shown in Fig. 2, driving mechanism 6 includes a drive shaft 7 and a driven shaft 8, the former being driven from gate 1 by suitable means, as for example a pinion 9 which meshes with rack 4, and the latter being coupled to the operating screw 5 of limit switch LS. Said driving mechanism also includes a releasable coupling 10 for connecting drive shaft 7 to driven shaft 8, a circular cam element 11 for effecting release and engagement of said coupling and an intermittent gear drive 12 between said cam element and drive shaft 7 for operating said cam element to effect engagement of said coupling during movement of gate 1 in zones Z¹ and Z² and to effect release of said coupling during movement of said gate through the remainder of its operating range.

More specifically, coupling 10 comprises a pair of flanges 13 and 14, the former being fixed to drive shaft 7 and the latter being keyed to driven shaft 8 to rotate therewith and to permit axial movement thereon. Flange 14 carries a pair of pins 15 and upon movement of said flange toward the left out of the position shown in Fig. 2 said pins engage within openings 16 in flange 13 to couple drive shaft 7 to driven shaft 8. Flange 14 also carries pins 17 which engage within openings 18 in fixed stops 19 to lock driven shaft 8 against rotation when said flange is moved into the position shown in Fig. 2. Flange 14 is operatively connected to cam element 11 by a shifter element 20 which is pivotally mounted upon a stationary pin 21. Said shifter element is provided with operating rollers 22 and 23 for engaging opposite sides of flange 14 and the same is also provided with rollers 24 and 25 for engagement with opposite sides of cam element 11.

Cam element 11 is rotatably mounted upon drive shaft 7 and is provided with two cam seg-

ments 26 and 27. As shown in Fig. 3 cam segment 26 extends through an angle of substantially 288 deg. and is provided with radially disposed beveled end faces 26^a and 26^b which cooperate with roller 24 to operate shifter element 20 for movement of coupling flange 14 into the disengaged position shown in Fig. 2. Cam segment 27 is arranged between the end faces of cam segment 26 and as shown in Fig. 3 the same extends through an angle of substantially 72 deg. Cam segment 27 is provided with radially disposed beveled end faces 27^a, 27^b which cooperate with roller 25 to operate shifter element 20 for movement of flange 14 into engaged position.

As shown in Fig. 2, the intermittent gear drive between cam element 11 and drive shaft 7 comprises three intermittent gear sets A, B and C, each consisting of a gear wheel 29, an operating arm 30 and a locking disk 31. Each of the gear wheels 29 is provided with five equally spaced radial slots 32 and is further provided with concave circular faces 33 which extend between said slots. Each of the arms 30 is rotatably supported at one end and has an operating pin 34 mounted upon its free end which momentarily engages within one of the slots 32 of its associated gear wheel during each revolution of said arm to effect quick rotation of said gear wheel through one-fifth of one complete revolution. Each of the locking disks 31 is fixed to its associated arm 30 to rotate therewith and is provided with a circular surface 36 for engaging the surfaces 33 on its associated gear wheel 29 to lock the latter against rotation immediately after the same is operated by its associated pin 34.

Gear wheel 29^a, arm 30^b and gear wheel 29^c of gear sets A, B and C are rotatably mounted upon drive shaft 7 and arm 30^a, gear wheel 29^b and arm 30^c of said gear sets are rotatably mounted upon a fixed supporting shaft 38. Arm 30^a is fixed to a gear 39 which is rotatably mounted upon shaft 38 and is driven from drive shaft 7 by a gear 40. Arm 30^b is fixed to gear wheel 29^a to rotate therewith and is disposed in radial alinement with one of the slots thereof, and arm 30^c is fixed to gear wheel 29^b to rotate therewith and is also disposed in radial alinement with one of the slots thereof. Gear wheel 29^c is fixed to cam element 11 in the angular position shown in Fig. 3 so that roller 25 is located midway between the end surfaces 27^a and 27^b of cam segment 27 when said gear wheel is locked by its associated disk 31^c in the angular position shown in this figure.

As is apparent, when arm 30^a of the afore-described intermittent gear drive 12 is rotated in either direction gear wheel 29^c is quickly stepped ahead one-fifth of one revolution each time said arm completes 25 revolutions so that cam element 11 is maintained in each of five equally spaced operating positions during substantially 25 revolutions of arm 30^a. Fig. 3 illustrates cam element 11 in one of its operating positions and when the same is rotated in either direction out of such position, cam segment 26 engages roller 24 to move coupling flange 14 into the disengaged position shown in Fig. 2. Upon return of cam element 11 in either direction into the operating position shown in Fig. 3, cam segment 27 engages roller 25 to move coupling flange 14 into its engaged position. As is apparent, cam segment 26 operates to maintain coupling flange 14 in disengaged position during substantially 100 revolutions of arm 30^a and cam segment 27

operates when moved in either direction into the operating position shown in Fig. 3 to maintain said coupling flange in engaged position during substantially 25 revolutions of said arm. It should be noted that arms 30 of the several gear sets are of such length that the angular speed of arm 30^c with respect to arm 30^a is multiplied at the moment said arms move through the angular positions shown in Fig. 2. Also it should be noted that the beveled end faces a and b of cam segments 26 and 27 operate to effect substantially instantaneous movement of coupling flange 14 between its engaged and disengaged positions at moments when said arms are moving in one direction or the other through the angular positions shown in Fig. 2. Gears 39 and 40 may be of various ratios, as for example a 1 to 1 ratio which provides for one step of operation of cam element 11 for 25 complete revolutions of drive shaft 7, and coupling flange 14 is angularly positioned on said drive shaft so that its openings 18 are aligned with the openings 18 in stops 18 at the moment coupling flange 14 is shifted into its engaged or disengaged position.

Assuming that drive shaft 7 is operatively connected to gate 1 so that the same makes one complete revolution for each foot of travel of the gate and that gears 39 and 40 have a 1 to 1 ratio. Also assume that the intermittent gear drive 12 is set with respect to gate 1 so that at the moment said gate moves into the upper and of closing zone Z¹ cam segment 26 engages its associated roller 24 to move coupling flange 14 into its disengaged position. As is apparent from the foregoing, cam segment 26 then operates to maintain coupling flange 14 in disengaged position for disconnection of limit switch LS from drive shaft 7 during 100 ft. of travel of the gate in either direction between the lower and upper zones Z¹ and Z². However, when gate 1 is moved upwardly into zone Z² or downwardly into zone Z¹ cam segment 27 operates to move coupling flange 14 into its engaged position for operation of limit switch LS in these zones. As is apparent, limit switch LS may be adjusted to effect stopping of motor M upon 20 ft. of downward travel of the gate in zone Z¹ and upon 5 ft. of upward travel of the gate in zone Z².

The above described driving mechanism may be mounted within a suitable casing to provide a separate unit as shown in Fig. 1, or if desired the same may be embodied with the limit switch mechanism to provide a single unitary structure.

What we claim as new and desire to secure by Letters Patent is:

1. The combination with a motor driven device having a long operating range and a control device therefor having a relatively short operating range, of a rotatable drive shaft for said control device operable by said driven device during movement thereof throughout its entire operating range, a releasable coupling for connecting said control device to said drive shaft, and control means for said coupling including an intermittent gear operating connection between the same and said drive shaft for maintaining said coupling in disengaged position during movement of said driven device through a major part of its operating range and for engaging the same during movement of said driven device through the remainder of its operating range.

2. The combination with a reversible motor driven device having a long operating range and

a control device therefor having a relatively short operating range, of a rotatable drive shaft for said control device operable by said driven device during movement thereof throughout its entire operating range, a releasable coupling for connecting said control device to said drive shaft, and means for controlling said coupling to effect engagement thereof during movement of said driven device within predetermined short zones at opposite ends of its operating range and for effecting disengagement thereof during movement of said driven device between said zones, said means including an intermittent gear operating connection between said coupling and said drive shaft.

3. The combination with a reversible motor driven device having a long operating range and a control device therefor having a relatively short operating range, of a rotatable drive shaft for said control device operable by said driven device during movement thereof throughout its entire operating range, a releasable coupling for connecting said control device to said drive shaft, and means for controlling said coupling to effect engagement thereof during movement of said driven device within predetermined short zones at opposite ends of its operating range and for effecting disengagement thereof during movement of said driven device between said zones, said control means including a rotatable cam element for effecting release and engagement of said coupling, and an intermittent gear operating connection between said cam element and said drive shaft.

4. The combination with a reversible motor driven device having a long operating range and a control device therefor having a relatively short operating range, of a rotatable drive shaft for said control device operable by said driven device during movement thereof throughout its entire operating range, a releasable coupling for connecting said control device to said drive shaft, means associated with said coupling for positively locking said control device against operation upon release of said coupling, and means for controlling said coupling to effect engagement thereof during movement of said driven device within predetermined short zones at opposite ends of its operating range and for effecting disengagement thereof during movement of said driven device between said zones, said means including an intermittent gear operating connection between said coupling and said drive shaft.

5. The combination with a control device having a short operating range, of a drive shaft therefor having a relatively long operating range, a releasable coupling for connecting said device to said shaft, an operating connection between said coupling and said shaft including an intermittent gear drive, and means controllable by said intermittent gear drive for effecting release and engagement of said coupling, said coupling being operatively connected at all times to said shaft through the medium of said intermittent gear drive, and said intermittent gear drive acting to maintain said coupling in released position during movement of said shaft throughout a major part of its operating range and then effecting engagement of said coupling throughout the remainder of the operating range of said shaft.

6. The combination with a control device having a short operating range, of a drive shaft therefor having a relatively long operating range, a releasable coupling for connecting said device

to said shaft, a cam element for effecting release and engagement of said coupling, and an intermittent gear drive between said cam element and said shaft, said cam element being operatively connected at all times to said shaft through the medium of said intermittent gear drive, and said intermittent gear drive per se acting to control said cam element to effect engagement of said coupling during movement of said drive shaft within predetermined short zones of opposite ends of its operating range and to effect disengagement of said coupling during movement of said drive shaft between said zones.

7. The combination with a reversible motor driven device having a long operating range, a limit switch for stopping said motor driven device at opposite ends of its range, said limit switch having a relatively short operating range, of a rotatable drive shaft for said limit switch operable by said driven device during movement thereof throughout its entire operating range, a releasable coupling for connecting said limit switch to said drive shaft and an operating connection between said coupling and said drive shaft including an intermittent gear drive, and means controllable by said intermittent gear drive for effecting engagement and disengagement of said coupling, said coupling being operatively connected at all times to said shaft through the medium of said intermittent gear drive, and said intermittent gear drive acting to effect engagement of said coupling during movement of said driven device within predetermined short zones at opposite ends of its operating range and to effect disengagement of said coupling during movement of said driven device between said zones.

8. The combination with a movable element having a long range of movement, of a limit switch therefor having a relatively short range of movement, a rotatable drive shaft for said limit switch operable by said movable element during movement thereof throughout its entire range, a releasable coupling for connecting said switch to said drive shaft, and means for controlling said coupling to effect engagement thereof during movement of said movable element within predetermined short zones within its operating range and for effecting disengagement thereof during movement of said element between said zones, said means including an intermittent gear operating connection between said coupling and said drive shaft.

9. The combination with a movable element having a long operating range, of a limit switch therefor having a relatively short operating range, a rotatable drive shaft for said limit switch operable by said movable element during movement thereof throughout its entire operating range, a releasable coupling for connecting said switch to said shaft, and means for controlling said coupling to effect engagement thereof during movement of said movable element within predetermined short zones within its operating range and for effecting disengagement thereof during movement of said movable element between said zones, said control means including a rotatable cam element for effecting release and engagement of said coupling, and an intermittent gear operating connection between said cam element and said drive shaft.

10. The combination with a movable element having a long operating range and a limit switch therefor having a relatively short operating range, of a rotatable drive shaft for said limit switch operable by said movable element during

movement thereof throughout its entire operating range, a releasable coupling for connecting said switch to said shaft, means associated with said coupling for positively locking said control device against operation upon release of said coupling, and means for controlling said coupling to effect engagement thereof during movement of said movable element within predetermined short zones within its operating range and for effecting disengagement thereof during movement of said movable element between said zones, said control means including a rotatable cam element for effecting release and engagement of said coupling, and an intermittent gear operating con-

nection between said cam element and said drive shaft.
